(57) **CLAIM**

We claim the ornamental design for a food dispenser, as shown and described.

DESCRIPTION

FIG. 1 is a top, front, right perspective view a food dispenser showing the new design;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof; and,

FIG. 7 is a bottom plan view thereof.

The long dash, short dash broken lines (i.e., dash-dot) define bounds of the claimed design and form no part of the claimed design. The food dispenser is shown broken in places along the height and length directions in FIGS. 1-7 to indicate indeterminate length, with the understanding that the “indeterminate” length portion of the food dispenser not shown forms no part of the claimed design. Patentability is based only on those portions of the article that are shown in solid lines. The remaining broken lines in the figures depict portions of the food dispenser that form no part of the claimed design.
